UNITED STATES PATENT OFFICE.

VINCENT V. VEENSCHOTEN, OF ERIE, PENNSYLVANIA.

FEED-WATER REGULATOR.

Application filed December 16, 1918. Serial No. 266,369.

To all whom it may concern:

Be it known that I, VINCENT V. VEENSCHOTEN, a citizen of the United States, residing at Erie, in the county of Erie and State of Pennsylvania, have invented certain new and useful Improvements in Feed-Water Regulators, of which the following is a specification.

This invention relates to feed-water regulators, and particularly to regulators which are adapted to generate steam, the pressure of which depends upon the elevation of the water in the boiler, and to operate by this steam the feed-water valve. In general the object of the invention is to provide improved means for controlling the water-level elevation in the boiler, particularly with reference to the demand for steam on the boiler, and to provide suitable adjusting means for such purposes.

Of the accompanying drawings Fig. 1 is an elevation more or less diagrammatic of a boiler, and a boiler feed-water regulator connected therewith which embodies features of my invention. Fig. 2 is a central sectional view of the regulator and the feed-water valve controller and the valve. Fig. 3 is an elevation of the controller and valve; and Fig. 4 is a modified form of the feed-water valve controller.

The regulator 19 comprises a tube 27, which is connected, by means of pipes 28 and 29, above and below the water-level in the boiler 30. The tube 27 therefore has more or less steam in its upper end and water in its lower end, depending upon the elevation of the water-level in the boiler. Enclosing this tube 27 is a tube 31 partly filled with water 32, and the tube 33, the tank 34 and the tube 35 connect the tube 31 with the diaphragm controller 36.

In operation, as the water in the boiler sinks steam will be generated in the tube 31 of the regulator, due to the increasing amount of steam in the tube 27; and the pressure of the steam generated will depend much upon the elevation of the water in the tube 27. Thus the pressure of the steam generated, and hence the fluid pressure in the diaphragm chamber 44 will depend more or less on the elevation of the water in the boiler; and this pressure in turn, by means of the diaphragm and the members connecting it with the plunger 37, will determine the po-

sition of the plunger; and hence will determine the amount of flow of water to the boiler through the feed-water valve 39.

In use it has been found that the amount of water in the regulator tube 31 continually decreases, and has to be replaced periodically; so that the water-level in the tube may vary greatly, and hence is often a material distance below the water-level in the tube 27, when the latter level is high, although in practice it should be above the latter level. These irregularities materially affect the steam pressure generated in the tube 31 under similar conditions. This is much increased, ordinarily, by connecting the tube 33 to the lower end of the generator. When thus arranged as the water-level in the boiler sinks the water in the tube 31 is forced down into the diaphragm chamber, and hence the water level in the tube sinks materially lower.

To maintain more nearly uniform the elevation of the water in the tube 31, I have connected the pipe 33 to the tube 31 at substantially the desired water-level elevation in the tube; and have also connected the tube 33 with the reservoir 34. This reservoir has a very material horizontal cross section compared with the smaller section of the generator tube 31, and, hence, by the insertion of the reservoir in the manner shown, the water-level in the tube 31 will be maintained at substantially the same elevation as the water-level in the reservoir, because, as the water in the tube 31 passes off by leakage of steam or otherwise, the water will flow from the reservoir into the tube; and, in addition, it is impossible for the water in the tube 31 to be forced below the entrance to the tube of the pipe 33.

In order to supply water to the reservoir 34 any suitable means may be provided. I prefer for this purpose a pipe 40 connected with any suitable source of water supply under pressure, passing downwardly from the reservoir to a point where it can be conveniently reached by the operator in charge. I provide, also, a similar pipe 41 leading to the same point, and which is adapted to release the pressure in the reservoir so as to allow the water to flow into the reservoir when both valves 37 and 38 are opened. The pipe 41 opens into a sink, or other suitable receptacle; and the water will flow therefrom as soon as the reservoir is sufficiently

filled; and this will indicate to the operator the fact that sufficient water has been supplied.

By the use of the generator, with the automatic water-level controller 34 therefor, maintaining substantially uniform the water-level in the tube 31, the pressure of the steam in the tube 31 varies inversely with the elevation of the water-level in the tube 27, and hence in the boiler 30; and hence the opening of the feed-water valve varies correspondingly. As a consequence, if the various elements are properly proportioned and adjusted, the elevation of the water in the boiler will vary inversely with the demand for steam, or with the load on the boiler. However, the sensitiveness of the coaction between the regulator and the boiler water-level depends upon the sensitiveness of the movement of the valve plunger to the variations in steam pressure in the generator. To increase this sensitiveness I provide operating means connecting the diaphragm to the valve plunger which comprise the rotating spindle 42 rotatably mounted in and passing through the stuffing box 43, instead of the ordinary form of reciprocating valve stem, thereby materially reducing the force required to operate this connecting mechanism.

In order to provide for movement of the valve plunger unlike the movement of the diaphragm, the lever arm 45 may be made longer or shorter than the lever arm 46; if longer the movement of the diaphragm will be more than the movement of the valve plunger, and if shorter the movement of the diaphragm will be less. To adjust the relative movements of these two elements I provide openings 47 in the lever arm 45, so that the connecting stem 48 may be connected to the arm where desired; and in order to allow the stem 48 to be always substantially vertical I provide openings 49 in the frame 50 so that the diaphragm yoke 51 may be shifted to the proper position on the frame to maintain a vertical position of the stem.

Variations in the relative movement of the diaphragm and the plunger are desirable in order to vary the variations in boiler water-level elevations due to the variations in load on the boiler; the greater the relative movement of the valve plunger the greater the amount of variation in water inflow for a given change in diaphragm movement, and hence for a given change in water-level elevation. As a consequence the greater the relative movement of the valve the smaller will be the variations in the boiler water-level elevations due to variations in load.

In operation as the feed-water valve

opens more and more the drop in water pressure therethrough ordinarily decreases and, if the plunger ports 55 have parallel sides, the flow of water therethrough does not increase in proportion to the movement of the valve. As a consequence, the rate of change of the water-level elevation in the boiler, due to changes in load will be less with heavy loads than with light loads; while, if there is any difference, it is usually preferable to have the greater effect with heavy loads than with light loads, as variations in boiler water-level elevations with heavy loads is more dangerous than with light loads.

Therefore, to offset the drop in pressure through the valve with increasing inflow, I provide the non-parallel ports through the plunger so that as the plunger opens further, and the drop in pressure therethrough decreases, the area of the openings of the ports will increase at a rate greater than the actual movement of the plunger. By properly forming the angle between the sides of the port the inflow may be maintained proportional to the movement of the plunger, or, if desired, it may be made to increase at a greater rate than the movement of the plunger and to thereby cause the water-level variations with heavy loads to be less, for a given change in water-level than with light loads.

Fig. 4 shows a modified form of the means for connecting the diaphragm with the valve plunger comprising the levers 60 and 61, connected respectively to the diaphragm and to the plunger, so that a double leverage is produced, and the movement of the plunger is materially greater than the movement of the diaphragm; and the amount of the relative movements of the two may be varied by means of the openings 62 and 63 in the levers, the fulcrum of the lever 60 being varied accordingly by means of the openings 64.

I claim as my invention:

The combination of a feed-water valve having a casing, and operating means for operating said valve, and a frame for supporting said operating means fixed with reference to said valve casing, means operatively connecting said operating means and said valve, said latter means comprising an arm operatively connected with said valve, and means for adjusting the position of said frame with reference to said casing in a direction substantially parallel with said arm, and means for correspondingly shifting the connection of said operating means with said arm.

In testimony whereof, I hereunto set my hand.

VINCENT V. VEENSCHOTEN.
